BOILER TUBE CLEANING APPARATUS

Charles S. Turner, Detroit, Mich., assignor, by
mesne assignments, to Diamond Power Spe-
cialty Corporation, Detroit, Mich., a corpora-
tion of Michigan

Application February 15, 1930, Serial No. 428,721

11 Claims. (Cl. 122—392)

This invention relates to boiler tube cleaning apparatus, and has for its object an improved organization of parts whereby the efficient removal of soot accumulation on individual boiler tubes may be effected without interferences with the continued operation of the boiler to which the tubes are appurtenant. The mechanism herein disclosed permits the effectuation of this desired result without involving the impairment 5 of the blower tube at intervals generally corresponding to the spacing of the boiler tubes which would otherwise occur if an entirely separate pipe were used for the latter purpose. One form 10 in common use of which I am aware travels the space occupied by the tubes in a direction perpendicular to the axial extent of these latter, and consequently is subjected at intervals along its length to impairing variances of thermal conditions due to the alternated proximity or other- 15 wise of specific points therealong to the boiler tubes themselves, which are capable of exerting a marked cooling influence by absorbing heat therefrom in considerable quantities, the boiler tubes being themselves cooled by the steam and 20 water within them, while the blower tubes ordinarily remain empty during the greater portion of the time in which the boiler is in operation. 25

It is an already ascertained fact in boiler work, that where tubes are used, and where there is a 30 resultant marked variance between the thermal conditions prevailing within the tubes and in the space surrounding and separating them, for a space immediately surrounding the outer walls of each tube generally not in excess of an inch 35 and a half therefrom, a great deal of the heat prevailing in the spaces between said tubes is absorbed or drawn into the metal of the latter because of the high heat conductivity thereof, but that as to any space much in excess of this tem- 40 peratures increase rapidly, so that there will be spots or areas in the spaces between said tubes wherein an undesirably greater degree of heat prevails and cannot be conductively reduced as regards impairment of any metal parts positioned 45 therein in whole or in part. In other words, if the spacing between the tubes be not in excess of three inches, this shortest distance between them will represent an area or zone, possibly somewhat overlapping if the spacing of the tubes 50 be less than three inches, wherein there is a high degree of drawing away of heat by the walls of the tubes themselves aided by whatever fins or the like may be present; but interspersed with these spaces there will, even under these 55 conditions, be spaces, to which reference will

hereinafter be made diagrammatically, from which the heat is not efficiently drawn away. Aside from the undesirability of being thus limited to a maximum space of three inches between all adjacent boiler tubes, and the relatively small 5 size of any blower pipe which can accordingly be passed between them in a direction axially transverse thereof, there will thus appear in the metal wall of the blower tube at intervals alternated with the boiler-tube-aided portions of the 10 pipe, spots or spaces where, due to the high heat conditions prevailing, rapid impairment or warping of the metal wall will take place.

Attempts have been made to obviate this difficulty by the selection of some special metallurgical element or mixture for use in the construction of the blower tube pipe, which would render it of relatively high resistant character to heat, but these efforts have been of a dubious degree 15 of success, and I have approached the solution 20 of this problem from an entirely different angle, to wit: The fixed integration of the steam blower pipes with selected ones of the tubes and in generally longitudinal alignment therewith, so that the walls of the steam blower pipe portion 25 participate in the heat conduction or withdrawal influence already remarked upon as characteristic of the walls of the boiler tubes themselves.

Various embodiments of this are herewith offered in the drawings, wherein:—

Figure 1 is a perspective of an installation, wherein, for the sake of simplicity, but one set of the tubes whose cleansing is desired, is shown 30 as extending between the headers or drums.

Figure 2 is a side elevational view of such an installation, showing a blower pipe and several tubes whose cleansing is desired, being in a more extended degree side elevationally representative 35 of the showing in Figure 1.

Figure 3 is a partly sectional plan view taken along the line Y—Y of Figure 2, showing a plurality of such parallel-arranged blower tubes and boiler tubes.

Figures 4, 5 and 6 are cross sectional representations on a large scale of various types of blower tubes and jets which may be employed in conjunction with boiler tubes which are also shown.

Figure 7 is a largely sectional representation 45 analogous to Fig. 2 of a somewhat modified system of boiler and blower tube assembly in which a single blower pipe is secured to any one boiler tube.

Figure 8 is a sectional representation showing 50 a slightly modified manner of feeding the steam 55

to the blower tubes, wherein the supply header or conduit is located within the confines of the boiler drum, with branches radiating each way to suitably positioned blower tubes secured to 5 all or selected ones of the boiler tubes, the blower tubes and jets therein being also of somewhat modified form.

Figure 9 is a plan view taken along the line 10 Z—Z of Figure 8, bringing out the extent of the 15 blower tubes on either side of the boiler wall and of the supply conduit, and the arrangement of the blower tubes.

Figure 10 is a partly sectional and partly diagrammatic view illustrating the positioning of 15 blower tubes in the manner herein disclosed within the zone or space of probable most effective heat absorption attributable to the walls of a boiler tube.

Figure 11 is an elevational view of a possible 20 modified form of structural and thermal integration of the boiler tube and of the steam blower pipe, wherein the latter, instead of being arranged lengthwise of the blower pipe, is positioned spirally thereabout.

Figure 12 is a sectional view of another modified form of structurally integrated boiler tube and steam jet pipe, wherein the latter is of completely circular cross section and only peripherally touches the boiler tube, though also partly 30 encircled by a built-out extension from the wall thereof.

12 represents the wall or shell enclosing a boiler element of any desired constructional details, and 13 a lower drum from which the several series of 35 boiler tubes, as for example, 14 to 20, inclusive, or as many more or less as may be desired, lead to the upper drum or header 21. Positioned conveniently to the bank of boiler tubes, though externally of the lower chamber 13, and controlled 40 by a suitable valve, as 22, is a steam supply pipe 23, from which lead various branch supply pipes as 40 connected to blower tube passages 24 to 29 inclusive, secured and respectively appurtenant to the tubes of the plain boiler tube series 14 to 45 20. In Figure 3 boiler tubes thus equipped with integrated steam blower pipes are shown positioned only upon every alternate one of the series of boiler tubes, 14 to 20, inclusive, as upon the boiler tubes 15, 17 and 19, which alternated 50 arrangement is, under some circumstances, adequate, the preferable form of steam jet nozzle there employed being the doubly apertured type illustrated cross-sectionally in Figure 10, wherein the jet apertures 43 and 44 direct their cleaning 55 blasts on either side of the straight row of plain boiler tubes with which their respective integrated boiler tubes 15, 17 and 19 are aligned. The lower passage tubes extend in general parallel relation to the several supporting and thermally integrated 60 boiler tube elements, to the degree of being each appended and so far as possible metallurgically integrated with the wall of the particular boiler tube on which it is severally carried, preferably, as shown in Figures 1, 2 and 8, 65 on the side farthest from the source of heat, which is of course positioned generally below the tube banks. Whichever of the particular structural embodiments thereof, which are suggested 70 in the several cross-sectional figures, are used, the more or less grafted-on steam blower pipe portion of each, as 41, for example, in Figure 5, or 43 and 44 in Figure 4, is of such size that its outer peripheral point does not lie farther away from the boiler tube wall than the approximate inch 75 and one-half mentioned in an earlier paragraph

hereof as the maximum distance away from such wall from which it can effectively draw away heat units. And of course the more nearly perfect the metallurgical union of the boiler tube wall and of the steam pipe wall, the greater is the degree of heat conduction which may reasonably be expected to take place. The desired restriction of the radial extent of the steam blower pipe relatively to the boiler tube is brought out in partly sectional and partly diagrammatic Figure 10, wherein the dotted circle V represents the outer border or edge of the one and one-half inch zone heretofore referred to, and the space between that and the dotted circle U represents a zone so far removed from the boiler tube wall that the latter is incapable of participation to any effective degree in absorbing heat therefrom.

Carrying this illustrative comparison one degree further, I have indicated at 55 in Figure 3 a more or less diamond-shaped space bounded 20 by four boiler tubes, which, even if the space between the latter be not in excess of a total of three inches, will still be left without efficient heat-removal, and will consequently have prevailing within it such a relatively high temperature that heat-impairment of a steam blower tube positioned within it would almost inevitably take place, since such blower tubes, being empty during the greater part of the time during which the boiler is in operation, have not the cooling 30 influence of contained steam or water, as have the boiler tubes. So long as efficient heat conduction is provided for between them, and the blower tubes are kept close to the boiler tubes, in the manner described, the boiler tubes can 35 assist in keeping the blower tubes at a safely low temperature by absorbing heat from them.

An alternative arrangement to that suggested in Figure 3 is shown in Figure 4, wherein the blower jet openings 50 and 51 are so positioned 40 as to discharge on either side of their corresponding row of boiler tubes. If, however, it is desired to position the steam supply tubes in other than the direct alignment with their corresponding tubes shown in Figure 3, as for example, midway between adjacent rows thereof, either of the single jet forms of steam or other fluid spray shown at 41, 41' with peripheral jet openings 48, 49 in Figures 5 and 6, may be employed. It will be noted that in all of the cross-sectional 45 variances illustrated, for example, in Figures 4, 5, and 6 the blower tubes are not of truly circular cross section, but rather bound a more or less crescent-sectioned area, and are metallurgically integrated with the boiler tube wall, as by welding thereto the lateral edges of an, in itself, troughed or cross-sectionally semi-circular member, which may, as shown, have no wall on the boiler tube side. The purpose of this is, of course, the restriction of the outer curved peripheral portion thereof when 50 applied to the boiler tube to a position as close thereto as possible, so that heat conduction between them may be as rapid and efficient as is possible, which would not be the case to any such degree if a fully circular steam blower pipe were 55 used. It will be obvious that, subject to the supplying of a cleansing steam flow and its control by means of a valve as 22, cleansing jets of steam or other fluid, may be projected against the surfaces of the several boiler tubes, without interference with the continued operation of the latter as component elements of the boiler structure as a whole.

My preferred positioning of the branch steam supply pipes 40 in the embodiment in which they 75

are arranged outside the lower drum, so that they lie as close as possible to the boiler tubes, for most effective heat dissipation, is shown in plan in Figure 7, while as also therein shown the 5 blower tubes are arranged in direct line with the several boiler tubes to which each is appurtenant, so that the blower tubes are protected against direct impingement by radiant heat and the most highly heated gases.

10 In the modified form of construction shown in Figures 8 and 9, I position the steam supply header 31 within the boiler drum or wall 32, and lead therefrom, in different directions, branch steam jet supply pipes 33 and 34 which, with their supporting boiler tubes pass through the wall of the 15 drum 32 to direct connection with the channels 35 and 36, respectively, which are equipped at suitable intervals with steam spray nozzles of any desired form. In the form shown these 20 nozzles as 44', are arranged to clear not only the steam pipes adjacent to them in the series as arranged, but as well, their own supporting pipes 37 and 38.

In the modified construction shown in Figure 25 10, I have illustrated the structural and thermal integration of a boiler tube 46 and of a steam pipe 47 appendingly associated therewith in a spiral rather than a longitudinal direction, although my experience leads me to the opinion that 30 this is a less satisfactory construction in an operative sense than the straight longitudinal construction shown in most of the other figures of drawing, as well as being more expensive to manufacture. I illustrate this in order to further elucidate the scope which I desire assigned to my 35 disclosure of the idea of integrating a boiler tube and a steam supply pipe in some manner which will fixedly locate the steam supply pipe within the zone of thermal conductivity by the walls 40 of the boiler tube in the manner and to the degree heretofore indicated.

Fig. 12 represents a modified construction in which the union between the boiler and soot blower tubing, each individually complete and cylindrical, 45 is preponderantly structural rather than metallurgical. In this figure the steam blower pipe 52, provided with jet apertures 53 at suitable intervals along its length, really only peripherally touches the boiler tube, as 24, but is surrounded by a heat- 50 conductive elongated clamp or similar attaching element 54 extending outwardly from the boiler tube wall, to which it may be welded, on either side of the lower tube. Through the member 54 effective heat-conduction takes place between the 55 tubes 14"—52, though probably not with the degree of efficiency expectable from the more thoroughly and intimately integrated structural associations of the steam pipe and the boiler tube wall in the embodiments previously described. I 60 therefore desire my disclosure in the preceding paragraphs and the use of such language ascriptive thereof in the claims, to be considered as embodying the equivalency of the words "structurally" and "metallurgically", accordingly. In 65 any and all of these forms the same principle is followed as regards the restriction of the diametrical extent of the steam blower pipe away from the wall of its supporting boiler tube within the indicated limit of thermal conductivity by 70 the latter of the higher temperature units to a degree which will prevent oxidation and resultant impairment of the walls of the blower and steam conductor pipes. While, as heretofore stated, approximately an inch and a half is the now 75 understood standard maximum for this, I do not

wish this disclosure to be understood as restricted to just these indicated limits. Of course the presence of the attached steam pipe, connected and in some cases actually metallurgically integrated, with the boiler tube, within the limits of this zone of heat conduction materially aids and increases the degree of absorption of the heat units by the boiler tube wall, in effect offering a line of easiest travel therefor.

And while I have in my disclosure generally used the word "steam" as illustrative of the tube-cleaning element employed, I desire this to be considered as including any fluid appropriate for the purpose, even air, if desired.

What I claim is:

1. In combination with a plurality of spacedly arranged boiler tubes located in position of relatively probable soot precipitation upon their external surfaces, a blower pipe integrally secured to the wall of one of said tubes and connected 20 with an external fluid supply source, the passage formed by the blower pipe being separated from the passage formed by the boiler tube to which the blower pipe is secured by a common wall, such blower pipe being provided with spaced jet openings through which the fluid may forcibly emerge against the surfaces of its several neighboring boiler tubes to effect the dislocation therefrom of deposited matter, the direction of such fluid emission being generally coincident with the direction of gas flow past the tubes.

2. In combination with a boiler and a plurality of boiler tubes therein having portions substantially spaced from the boiler walls, a soot blower installation including a blower passage member 35 united with one of the boiler tubes, all portions of which blower passage member arranged within the hotter portions of the boiler lie within a radial distance of one and one half inches from the surface of the boiler tube.

3. In combination with a boiler and a plurality of boiler tubes therein having portions substantially spaced from the boiler walls, a soot blower installation including a blower passage member 45 united with one of the boiler tubes, all those portions of which blower passage member which are in greatest need of protection against burning out being arranged to lie in an unbroken path of heat conduction extending to the boiler tube and not longer than one and one half inches.

4. In combination with a boiler and a plurality of boiler tubes therein having portions substantially spaced from the boiler walls, said boiler tubes being spaced from each other in such a manner that the space between the outer surface of one tube and the outer surface of an adjacent tube does not exceed three inches, a soot blower installation including a blower passage member 55 intimately metallically united with one of the boiler tubes and extending radially from the outer surface of said tube toward an adjacent tube, all points of which blower passage member which lie in its parts most liable to burning out being arranged in paths of direct and unbroken metallic heat conduction extending to the boiler tube and not longer than two inches.

5. In combination with a relatively isolated boiler tube of a steam boiler, a soot blower including a channel member extending along and welded to the leeward side of the boiler tube, all those portions of which channel member subjected to highest temperatures lie within a distance of one and one-half inches from the tube.

6. In combination with a relatively isolated boiler tube of a steam boiler and a second tube

spaced therefrom a distance not exceeding three inches, a soot blower including a channel member welded to the first mentioned tube and extending toward the second mentioned tube, all portions of which channel member which are in greatest need of protection against burning out being arranged to lie within two inches of the tube.

7. In combination with a spaced boiler tube of a steam boiler, a soot blower including a channeled member extending along the leeward side of the boiler tube and so integrated therewith as to provide an efficient and unbroken heat bridge between them, all portions of said channeled member which lie within the hotter portions of the boiler being less than one and one-half inches from the boiler tube.

8. In combination, a boiler tube, and means providing a blower element in juxtaposition to said boiler tube, said means being wholly within a radial distance of one and one-half inches from the surface of said boiler tube.

9. In combination, a boiler tube, and means

providing a blower element in juxtaposition to said boiler tube and integrally secured thereto, said means being wholly within the relatively cool zone immediately surrounding said boiler tube.

10. In combination, a boiler tube, and means integrally secured to the side of the boiler tube most remote from the source of heat providing a blower element extending longitudinally of the boiler tube, said means being wholly within the relatively cool zone immediately surrounding said boiler tube.

11. In combination with a relatively isolated boiler tube of a steam boiler, a soot blower including an arcuate shaped channel member extending along and having its longitudinal edges welded to the leeward side of the boiler tube, all those portions of which channel member subjected to highest temperatures lie within the relatively cool zone immediately surrounding the boiler tube.

CHARLES S. TURNER.
